Primary Examiner — Susan Bennett Hattan*Assistant Examiner* — Leanne Was(74) *Attorney, Agent, or Firm* — Husch Blackwell LLP(57) **CLAIM**

The ornamental design for a lid for a container, as shown and described.

DESCRIPTION

FIG. 1 is a top perspective view of the design of a lid for a container having a closure member attached thereto in a closed position;

FIG. 2 is a top perspective view of the lid for a container shown in FIG. 1 having a closure member attached thereto in an open position;

FIG. 3 is a top plan view of the lid for a container shown in FIG. 1 having a closure member attached thereto in a closed position;

FIG. 4 is a right side view of the lid for a container shown in FIG. 1 having a closure member attached thereto in a closed position;

FIG. 5 is a front side view of the lid for a container shown in FIG. 1 having a closure member attached thereto in a closed position;

FIG. 6 is a back side view of the lid for a container shown in FIG. 1 having a closure member attached thereto in a closed position; and,

FIG. 7 is a bottom plan view of the lid for a container shown in FIG. 1 having a closure member attached thereto in a closed position.

The features shown in broken lines depict environmental subject matter only and form no part of the claimed design.
